AIR POWER WATER PUMP

Filed April 8, 1921

Fig. 1.

Patented May 1, 1923.

1,453,486

UNITED STATES PATENT OFFICE.

JACOB A. AEBLY, OF WEST CONCORD, MINNESOTA.

AIR-POWER WATER PUMP.

Application filed April 8, 1921. Serial No. 459,557.

To all whom it may concern:

Be it known that I, JACOB A. AEBLY, a citizen of the United States, residing at West Concord, in the county of Dodge and State 5 of Minnesota, have invented certain new and useful Improvements in Air-Power Water Pumps; and I do hereby declare the following to be a full, clear, and exact description of the invention, such as will enable 10 others skilled in the art to which it appertains to make and use the same.

This invention relates to a liquid pump and especially to such a pump which is designed to be operated by compressed air.

15 It is an object of this invention to provide such a pump having water inlet and outlet valved passages, an air exhaust valve and an air inlet valve, the latter mentioned valves being operated entirely by floats and without 20 the use of springs or the aid of compressed air.

It is a further object of the invention to provide such a pump in which there are no small bleed or drain holes.

25 These and other objects and advantages of the invention will be apparent from the following description made in connection with the accompanying drawings in which like reference characters refer to the same 30 parts throughout the different views, and in which—

Fig. 1 is a longitudinal vertical section through the pump cylinder and other parts of the device;

35 Fig. 2 is a section taken on the line 2—2 of Fig. 1, looking in the direction of the arrows;

Fig. 3 is a section taken on the line 3—3 of Fig. 1, looking in the direction of the arrows; and

40 Fig. 4 is a partial transverse section of one of the floats.

Referring to the drawings, the pump comprises a cylinder 1 and the cylinder heads 2 and 3 located respectively at the top and bottom thereof. The cylinder and heads are united by a pair of spaced tie rods 4 extending therethrough adjacent the sides thereof and equipped with tightening nuts 45 at their threaded ends which project outside of the heads 2 and 3. The bottom cylinder head 3 has a depending portion 3^a forming a cylindrical chamber, the walls of which contain spaced apertures for the entrance of water, and said portion is surrounded by a screen 3^b. A central upstand-

ing portion in this chamber is bored to form a guide for the stem 5^a of the water inlet valve 5, the lower outer edge of which is provided with a suitable washer or gasket 60 and seats on a short upstanding flange extending from member 3.

The head 2 is of plate form and has upstanding from its upper side, three bosses 2^a, 2^b, 2^c, which are apertured to form, respectively the air exhaust passage, a water outlet passage and the air inlet passage. The boss 2^a has an apertured lug projecting from one side thereof and receiving the stem of an air exhaust valve 6 which is provided with a suitable washer or gasket seating against a short narrow flange depending from the inner side of the head 2. The boss 2^b will be provided with a check valve of any standard construction, such as shown in Fig. 1 and this 70 boss has extending from its inner side a water pipe or conduit 7 which has its lower open end disposed relatively near the bottom of the cylinder. The boss 2^c has a small opening 2^d extending from its lower portion 80 through the head 2 and this passage is formed with a conical enlargement to form a seat for the air inlet valve 8.

The head 2 has depending from its under side a pair of spaced lugs 9 and a lever 10 85 has lugs extending from either side at its rear end tapped to receive suitable pivots which extend into the lugs 9 to connect and pivot the lever thereto. The lever 10 comprises a pair of spaced weighted arms 10^a 90 and pins 11 extend from each of these arms to form pivots for the arms of a bifurcated member 12, from the central portion of the underside of which a tongue 13 depends having pins 14 extending a short distance 95 from either side of its outer end, the tongue 13 being rigidly secured to the member 12. The exhaust valve 6 is pivoted between the arms of the member 12 by the pivot pins 11. The lever 10 is formed with a vertically extending groove at its rear end and the valve 8 is disposed therein and pivoted to the side of the groove by a suitable pivot pin 8^a. The ends of the bifurcations of members 12, aline with and are adapted to engage with adjustable screws 12^a in spaced lugs 12^b depending from head 2.

A pair of float guiding rods 15 extend throughout the length of the cylinder in front of the tie rods 4 and a pair of float 110 members 16 and 17 of bi-cuspid shape are provided with grooves at each side thereof

loosely engaging said rods for vertical sliding movement thereon. The float 16 is provided with spaced upstanding lugs 18 which are provided at their upper ends with a narrow plate 18^a. The rear end of member 12 is bifurcated and traversed by a pin to which is pivotally hung a bar 19 which depends therefrom a considerable distance toward the bottom of the cylinder, and an arm 20 is fixedly secured to this bar at its lower end and projects forwardly to a cylindrical bearing formed on its front end, which receives a rod 21. This rod 21 is formed at its upper portion with a flat head engaging the top of bracket 20 and extends downwardly through a central aperture formed in float 17 and is threaded at its lower end to receive a retaining nut which is disposed in a cylindrical recess in the lower end of said float. An elastic or resilient collar 22 is pinned to the rod 21 adjacent the bearing 20. A curved baffle plate 23 is secured at its ends to the tie bars 4, the ends thereof being bent around the tie bars and riveted or otherwise secured together. This baffle plate extends in substantially parallel relation to the sides of the float and also extends for a considerable distance throughout the intermediate length of the cylinder. The float 16 is provided with upwardly extending members 24 which, when the float is sufficiently raised, are adapted to contact with the undersides of the arms 10^a of the lever 10.

The boss 2^a will, of course be connected by any suitable connection to the supply of compressed air. The boss 2^b will be connected to the water supply conduit to which it is intended to deliver the water while the boss 2^a will receive any suitable connection leading to the outside air or forming a suitable covering and protection therefor.

The operation of the device is as follows:

The cylinder will be submerged in the well or in the liquid which it is desired to pump. Assuming the pump is used as a water pump, the water will enter the cylinder through the openings in the lower head 3 and will rise therein filling the cylinder, it being assumed that the exhaust valve 6 is now open. The water will first raise the float 17, and this rising will, in turn, raise the bar 19 which will move the rear end of member 12 upwardly. At this time the lever 10 is swung down about the pivots 9 and is held in this position by the weighted arms 10^a. When the water rises sufficiently the float 16 will be raised and will come in contact with the lower end of the tongue 13. The members 24 on the float will now engage the underside of arms 10^a and lift the lever 10. As this lever is lifted, to the position shown in full lines in Fig. 1, the pins 14 on finger 13 will move under the plates 18^a so that the said plates are disposed centrally over said pins. When the lever 10 is raised to its upper posi-

tion, as shown in Fig. 1, the air exhaust valve 6 will be moved against its seat and the rear end of the lever swung down and air inlet valve 8 will be lowered from its seat. When the air exhaust valve is closed, the entrance of water into the cylinder will be substantially checked and the compressed air entering through the inlet valve opening 2^a will force the water in the cylinder out through the pipe 7, the valve 5 being forced against its seat.

As the water is forced out of the cylinder the float 16 will tend to descend, but owing to the engagement of the pins 18 with the plate 18^a, said float will be temporarily suspended on the finger or arm 13. The water continuing to leave the cylinder the float 17 will descend and carry with it the bar 19. As this bar is pulled downward it will swing the member 12 relatively to the lever 10 about the pivot pins 11 and the arms 13 will be moved forwardly bringing the pins 14 out of alignment with the plate 18^a. The ends of members 12 will then engage screws 12^a. This will release the float 16 and the same will quickly drop and will strike the head of the rod 21. This engagement will insure that the bar 19 moves to its lowest position and will also swing down the lever 10, this movement being assisted by the weighted arms 10^a. When the lever 10 swings downwardly the exhaust valve 6 is open and the air inlet valve 8 is closed. The pressure of the water will now open the valve 5 and the cylinder will refill and the described operation will be repeated.

The baffle plate 23 is provided to insure the even filling of the cylinder and is so located that it retards the upward movement of the float 16 insuring that the cylinder will entirely fill so that the floats will be properly operated.

From the above description it is seen that applicant has provided a simple and efficient pump. The air valves thereof are operated entirely by floats and without the use of springs and without the use of the compressed air used to discharge the water. The elimination of the springs removes very frequent cause of trouble and inoperativeness and since it is not necessary to use any of the compressed air for valve operation, such air is conserved and the pump is therefore more economical of the compressed air. It will also be noted that, unlike many of the pumps of the prior art, no small bleed or drain holes are required in the cylinder or in any of the valve openings. The elimination of such holes also does away with one of the great objections to this type of pump. In practice, the float 16 will be somewhat shorter in length than the float 17. One commercial size of the pump has the length of the cylinder between the heads forty-four inches with the upper float seven

inches long and the lower float eleven inches long. It will be understood, however, that the invention is not in any way limited to any particular size but may be made in any size desired.

It is also desired to point out that the pump has only two outside openings, one for the air exhaust and the other for the water inlet and the exhaust valve is operated entirely by the float and requires no auxiliary operating valve. The pump also has few parts for adjustment and when once installed for operation, has practically no tendency to become disarranged or inoperative.

The pump will preferably be equipped with an expansion chamber in the delivery line so that the delivery at a faucet or other point will be substantially continuous.

It will, of course, be understood that various changes may be made in the form, details and arrangement of the device without departing from the scope of applicant's invention, which, generally stated, consists in the matter shown and described and set forth in the appended claims.

What is claimed is:

1. A pump of the class described having in combination, a cylinder, a water inlet valve therefor, an air exhaust valve and an air inlet valve, and means for operating said air exhaust and inlet valves comprising water operated floats and connections therefrom to said valves and a weighted lever pivoted to the air exhaust valve.

2. A pump of the class described having in combination, a cylinder, upper and lower heads therefor, an air exhaust valve and an air inlet valve disposed in the upper head, a pivoted lever comprising spaced weighted arms between which the exhaust valve is pivoted and to which the air inlet valve is pivoted, said valves being disposed on opposite sides of the lever pivot.

3. A pump of the class described having in combination, a cylinder having upper and lower heads, a lever pivoted to the underside of the upper cylinder head, said pivot being disposed adjacent one end of the lever, said lever comprising spaced weighted arms extending from said pivot, an exhaust valve pivoted between said arms and co-operating with the seat carried in said head, an air inlet valve pivoted to the other end of said lever and co-operating with the seat in said head, and a float member in said cylinder having means to contact with said arms of the lever to operate the said valves.

4. A pump of the class described having in combination, a cylinder, upper and lower heads therefor, an air exhaust valve located adjacent the upper head, and an air inlet valve located adjacent the upper head, a lever pivoted adjacent one of its ends to the upper head to one end of which the air

inlet valve is pivoted, said lever comprising spaced weighted arms extending from its pivot between which the air exhaust valve is pivoted, a supplemental lever carried by said lever and pivoted at one end between said arms, a rod depending from the other end of said supplemental lever, and a float connected to said rod.

5. The structure set forth in claim 4, said supplemental lever having an arm depending therefrom, a float disposed above said first mentioned float having means thereon adapted to be engaged by said arm depending from the supplemental lever.

6. A pump of the class described having in combination, a cylinder provided with upper and lower heads, a lever pivoted adjacent one of its ends below the upper head, an air inlet valve connected to the short end of said lever, an air exhaust valve connected to the other end of said lever, an auxiliary member pivoted intermediate its ends to said lever, a float connected to one end of said member, the other end of said member being constructed and arranged to temporarily and removably engage a float.

7. The structure set forth in claim 6, and a float adapted to be temporarily engaged with the said other end of said member.

8. A pump of the class described having in combination, a cylinder provided with upper and lower heads, a lever pivoted adjacent one of its ends below the upper head, an air inlet valve connected to the short end of said lever, an air exhaust valve connected to the other end of said lever, a pair of float members for operating said lever, means on said lever for temporarily holding one of said floats suspended, and means operated by the other float to drop said first mentioned float to open the air exhaust valve and close the air inlet valve.

9. A pump of the class described having in combination, a cylinder provided with upper and lower heads, a lever pivoted adjacent one of its ends below the upper heads, an air inlet valve connected to the short end of said lever, an air exhaust valve connected to the other end of said lever, a member pivoted to said lever, a float, means connecting said float to said member, and a second float adapted to be engaged by said member and temporarily suspended thereby, said member being operated by said first mentioned float to drop the said second float.

10. The structure set forth in claim 9, the second float being arranged to drop onto said means to operate the said lever to open the exhaust valve and close the air inlet valve.

11. A pump of the class described having in combination, a cylinder, upper and lower heads therefor, an air exhaust valve and an air inlet valve disposed in the upper head,

a pivoted weighted lever to which the exhaust valve is pivoted and to which the air inlet valve is pivoted, said valves being disposed on opposite sides of the lever fulcrum.

12. A pump of the class described having in combination a cylinder provided with upper and lower heads, a lever pivoted adjacent one of the heads below the upper head, an air inlet valve connected to the short end of said lever, an air exhaust valve connected to the other end of said lever, an auxiliary member pivoted intermediate its ends to said lever, a lower float and an upper float, means connected adjacent one end of said auxiliary member and extending downwardly in the cylinder and adapted to be operated by said lower float, and means on said upper float adapted to engage and operate said lever.

13. A pump of the class described having in combination a cylinder having air inlet and exhaust openings in one end thereof, valves for controlling said openings, means for controlling said valves, comprising

ing a weighted bifurcated lever arm, a float permanently connected to said lever arm, and a float adapted to be temporarily connected to said lever arm member.

14. The structure set forth in claim 13, 30 said lever arm adapted to disengage said last mentioned float whereby the same will drop and insure the descent of the first mentioned float.

15. A pump of the class described having in combination a cylinder having compressed air and exhaust openings thereinto, valves for controlling said openings, and means for operating said valves comprising a weighted bifurcated lever arm, two floats, 40 one permanently connected to said lever arm to move with the liquid in said cylinder and the other adapted to be temporarily held above said liquid and then dropped.

In testimony whereof I affix my signature 45 in presence of two witnesses.

JACOB A. AEBLY.
